FLEXIBLE CLOSURE FOR DISPENSERS

Donald A. Jacobson, 7544 Park Ave. S.,
Minneapolis 23, Minn.

Filed Mar. 18, 1957, Ser. No. 646,708

3 Claims. (Cl. 222—507)

This invention relates generally to closures for bottles, tubes and the like, and pertains more particularly to a closure that will permit dispensing of the container's contents without first having to detach said closure or any part thereof from the container.

Although threaded caps have long been employed for sealing the openings on various types of containers, little argument exists that such closures are undesirable and inconvenient from a user's point of view. When measured over a prolonged period of use, the screwing and unscrewing of a threaded cap can involve a considerable amount of time and inconvenience. Also, such a cap is frequently apt to be lost or mislaid before it is re-applied to the tube or bottle. If dropped, even though it is not then lost, it immediately becomes unsanitary and should not again be utilized where cleanliness is important. Hence, it is believed readily apparent that there is an unsatisfied need for a closure that will not possess these shortcomings.

Accordingly, one object of the present invention is to provide a closure that does not involve the use of a threaded cap. More specifically, it is an aim of the invention to provide a closure of flexible material requiring only a simple back and forth sliding manipulation to effect either its opening or closing.

Another object is to provide a closure for containers that will be positive in its sealing action, thereby rendering the closure especially suitable for use in conjunction with collapsible containers such as toothpaste tubes and so called plastic "squeeze" bottles.

A further object is to provide a closure of unitary construction where there are no separable parts, thereby obviating the likelihood of one part becoming lost or misplaced.

Still another object of the invention is to provide a closure that is inexpensive to manufacture, it being contemplated that the deformable material be a plastic such as polyethylene. Since the previously alluded to familiar squeeze bottles are made of this material, it is envisaged that the closure structure be molded as a flexible integral part of such bottles. However, it is also planned that the closure be capable of use with tubes and the like equipped with metal ends, attachment being made thereto by means of threads or serrations.

Yet another object of the invention is to provide a closure of the foregoing character that does not require any additional squeezing action on the part of the user in dispensing fluid contents when my closure is attached to a collapsible container, such as a toothpaste or shaving cream tube.

Other objects will be in part obvious and in part pointed out more in detail hereinafter.

The invention accordingly consists in the features of construction, combination of elements and arrangement of parts which will be exemplified in the construction hereafter set forth and the scope of the application which will be indicated in the appended claims.

In the drawing:

2

Figure 1 is a fragmentary side elevational view of a plastic squeeze bottle equipped with my flexible closure;

Figure 2 is a sectional view taken in the direction of line 2—2 of Figure 1;

Figure 3 is an end view of Figure 1 in plan, the solid lines showing the closure open and the dotted lines showing the closure closed;

Figure 4 is a detail view of the slidable closure plate illustrating to better advantage the notched opening formed therein, and

Figure 5 is a modified version of the invention, this view corresponding generally to Figure 2 but illustrating a threaded connection of the flexible closure instead of the integral connection shown in the earlier embodiment.

Referring now in detail to Figures 1-3 of the drawing the embodiment there exemplifying my invention is illustrated as an integral molded portion of a plastic squeeze bottle 10. Such squeeze bottles have come into recent vogue, being usually formed of a thermoplastic material such as polyethylene. However, instead of the conventional threaded neck at the mouth of the bottle to which a screw type cap is ordinarily attached, there is employed my flexible closure designated generally by the numeral 12.

This closure 12 is preferably of the same plastic material as the bottle 10 and includes an elongated neck member 14 provided with a discharge passage 16 extending longitudinally therethrough. As can be seen from the end view presented in Figure 3, the passage 16 is convex at the top and bottom with the neck walls forming acute apices at the sides. The inherent resiliency of the plastic material constituting the neck member 14 is such that the passage 16 assumes the depicted configuration when not subjected to any closing forces, as will be referred to hereinafter.

Formed on the exterior surface of the neck member 14 is a pair of tapered ribs 18 providing inclined surfaces 19. These oppositely disposed ribs 18 diverge outwardly from the lower end or that end of the tubular neck lying adjacent the bottle 10, therefore having their greatest height located at the free or discharge end of the neck member. For a purpose soon to be made manifest these ribs 18 are provided with outwardly projecting lugs or stops 20 adjacent the discharge end of the closure 12. A slight notch or indentation 22 is formed at the base of each lug 20 for a reason also soon to be given.

Quadrantly disposed between the tapered ribs 18 is another pair of oppositely directed ribs 24. Close inspection of Figure 1 will reveal that these ribs 24 are provided with a slight taper that is the reverse of that imparted to the ribs 18, their height therefore being somewhat greater nearer the bottle 10. Accordingly, the ribs 24 provide what will be termed negatively inclined surfaces 25.

Encircling the neck member 14 is a ring element 26 in the form of a flat plate having an opening 28 therein. As best understood from Figure 4, the opening 28 is formed with a pair of oppositely issuing notches 30 into which the first pair of ribs 18 project, and a second pair of notches 32 for similarly accommodating the ribs 24. The notches 30 have base edges 34 and the notches 32 have base edges 36. The distance between the edges 34 is quite important, for it is these edges that are relied upon to force or cam the passage 16 closed at its discharge end, as will be presently explained. The distance between the edges 36 will also be dealt with below.

In using the bottle 10 or other container when equipped with my closure 12, attention is directed to the open position thereof pictured in Figures 1 and 2. From these two figures it will be noted that the ring element 26 has

been moved downwardly. In this position the edges 34 exert little or no closing force on the inclined surfaces 19 of the ribs 18. In other words the distance between the edges 34 is for all intents and purposes the same as that between the inclined surfaces 19 at this point. When the ring element 26 is moved upwardly in Figures 1 and 2, though, the edges 34 will bear with progressively increasing pressure against the sloping surfaces 19 of these ribs 18. By having the distance between the edges 34 equal to or slightly less (the plastic material will be 10 slightly compressible) than the distance between the inclined surfaces 19 of the ribs 18 at this end when the passage 16 is closed, the edges will act to wedge the passage into a closed condition whenever the ring element has been moved to the free end of the neck member 14. The phantom outline presented in Figure 3 shows this closed relationship. The edges 36 of the notches 32 should be spaced apart a distance sufficient to accommodate the expansion of the ribs 24 resulting from the foregoing deformation. Stated somewhat differently, the surfaces 25 of the ribs 24 will move laterally outwardly when the ribs 18 are forced closer together. Of course, by sliding the ring element 26 back toward the bottle 10, the inherent resiliency of the plastic material constituting the neck member 14 will re-open the passage 16.

It may be pointed out (Figure 2) that the lug 20 on each rib 18 will prevent the ring element 26 from becoming inadvertently dislodged from the neck 14. In this way the ring element 26 is held captive, though free to slide between opposite ends of the neck member 14. Yet at the same time, when the ring element has been moved to the free end, the presence of the notches 22 will assure that the ring element 26 will remain at this end and that the passage will consequently be forced closed until the ring element is intentionally slid to the end of the neck member adjacent the bottle 10, that is the position in which the ring element appears in Figures 1 and 2.

One thing to be noted is that the notches 30, 32 serve as guides for the ring element 26 throughout its slideable path, inasmuch as these notches are in respective engagement with the ribs 18 and 24.

To demonstrate further the versatility of the instant invention, attention is now directed to Figure 5. Here, instead of the bottle 10, there is a collapsible metal tube labeled 40 having a permanently attached threaded neck or collar 42. The closure in this instance has been denoted generally by the numeral 44 and includes a neck member 46. This modification differs only from the previously described embodiment by virtue of its having an internally threaded end 48 cooperable with the threads on the permanent neck 42. Accordingly, where the role played by each part is the same, duplicate reference numerals have been applied. Thus, if desired, the flexible closure 44 might be offered as a premium item or sold separately from the container, it then being contemplated that it would be used for a plurality of successively purchased containers. For instance, the closure 44 could be designed to fit the threads now utilized on the neck of a conventional toothpaste or shaving cream tube, and could be re-used for later acquired tubes merely by unscrewing the closure 44 from the first one. It will be understood that the annoyance of removing the ordinary screw cap is obviated, it only being necessary to switch 60 the closure 44 to a new tube after the contents of one tube has been completely used. The functioning of the closures 12 and 44 is identical.

Thus, in one embodiment the closure 12 is formed by having neck member 14 integral with the plastic squeeze bottle 10 and in another embodiment the closure 44 is formed by having neck member 46 threadedly attachable to tube 40. In both embodiments, ring ele-

ment 26 is used to effect the closing of discharge passage 16 by cooperating with the appropriately respective ribs.

As many changes could be made in the above construction and many apparently widely different embodiments of the invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim:

1. A closure for containers comprising: an elongated neck member of flexible, deformable material having a passage extending longitudinally therethrough; a pair of tapered ribs disposed along opposite sides of said neck member, said ribs diverging outwardly from a first end of said neck member to the other end of said neck member; and a ring element encircling said neck member having portions thereof slidably engaging said ribs to thereby force said other end of the neck member into a closed position when said ring element is moved into adjacency therewith.

2. A closure for containers comprising: an elongated neck member of flexible, deformable material having a passage extending longitudinally therethrough; a first pair of oppositely disposed ribs on the neck member tapering outwardly toward one end of said neck member; a second pair of oppositely disposed ribs on said neck member intermediate said first pair of ribs tapering inwardly toward said one end, said first and second pairs of ribs being quadrantly located with respect to each other; and a ring element in the form of a plate provided with an opening therethrough having quadrantly located notches for the accommodation of said ribs, whereby said ribs will guide said ring element when moved toward said one end of the neck member, the notches accommodating the first pair of ribs being so dimensioned with respect to said first pair of ribs that said first pair of ribs will be forced inwardly in the region of said one end to close said one end and the notches accommodating the second pair of ribs being so dimensioned with respect to said second pair of ribs that said second pair of ribs may be spread further into their respective notches without obstructive interference.

3. A closure in combination with a container comprising: an elongated neck member of flexible and deformable material having at least a pair of tapered ribs integral with said neck member to form inclined surfaces, said ribs having notches at an end furthest from said container, and a passage extending longitudinally therethrough, said passage including an enlarged section adapted to engage said container; and an element encompassing said neck member and adaptable to slide therealong engaging said inclined surfaces thereby deforming said neck material at said end furthest from said container and closing said passage, said element being further adapted to be held in locked position by said notches.
